UNITED STATES PATENT OFFICE

110,794

DESIGN FOR A HEEL

Emil Borman, Chicago, Ill.

Application January 3, 1938, Serial No. 74,050

Term of patent 14 years

To all whom it may concern:

Be it known that I, Emil Borman, a citizen of the United States of America, residing at Chicago, in the county of Cook and State of Illinois, have invented a new, original, and ornamental Design for a Heel, of which the following is a specification, reference being had to the accompanying drawing, forming a part thereof.

Fig. 1 is a perspective view of a heel, showing my new design.

Fig. 2 is a bottom plan view of the heel.

Fig. 3 is a side view of the heel.

I claim:

The ornamental design for a heel, as shown.

EMIL BORMAN.
